UNITED STATES PATENT OFFICE

HARRY J. CROCKER, OF BINGHAMTON, NEW YORK

FOOT ARCH AND METATARSAL SUPPORT

Application filed February 18, 1927. Serial No. 169,212.

My invention relates to supports for the arch of the foot, and metatarsal joints, and has for its object to provide a removable yielding support for the use in the shoe of the wearer, and adapted to the individual shoe and foot, and which can be used at intervals or constantly in connection with the shoe, and with but little expense, and without discomfort, and will produce healthful and restful results.

With these objects in view, my invention consists of the following novel features of construction and arrangements of parts as are more clearly hereinafter described and pointed out in the claims, reference being had to the accompanying drawings, in which:

Fig. 1 is a top plan view of my device.

Fig. 2 is an edge view partly in cross section of my device.

Fig. 3 is a bottom plan view of my device.

The same reference characters denote like parts in each of the several figures of the drawings.

In carrying out my invention, I provide an insole A, made of any suitable material which may have upon it the usual heel cover, or be without the heel cover. This insole may be made in different sizes, kinds of material and shape to conform to the foot and the shoe in which they are to be used. Mounted on the under side of the insole A I provide an elongated spring metal shank B, the rear end of which is fastened to the under side of the heel portion of the heel sole by the rivets 2, 2, or in any other adaptable manner. The forward end of the spring shank B rests free against the under side of the insole and the shank is curved slightly at the point 3 to conform to the natural shape of the foot arch. Over the free outer end of the shank B, I have mounted on the under side of the insole in any convenient manner, a flexible bottom cover or hood C into which the free end of the shank B extends and rests, permitting of a protection to the shoe bottom lining and at the same time permitting the free end of shank B to distend and contract on the insole bottom surface as the pressure movement of the foot resting upon the insole may produce. The hood C may be made of any suitable wearable mate-

rial such, for instance, as flexible resilient metal, leather or the like, and is made segmental in shape to permit the free end of the shank 3 to have a wide latitude of movement. The outer portion of the hood is arcuate in shape and extends across the insole beneath the arch portion. The insole A may be provided with the usual heel cover 4 or be without it. The spring shank B conforms to the arch of the foot while beneath the insole, and on the shoe bottom surface and affords a yielding resting support to the foot to sustain the arch. With a removable insole, such as shown in my invention it can be constantly left within the shoe or only occasionally used, affording a progressive strengthening relief which has a tendency to produce strengthening of the arch and bones of the foot.

In the operation of my device, the insoles forming a part of my device, are made in sizes to fit the shoes thereon, and may have thereon the usual indicia and size number, or they can be easily trimmed to fit the shoes on shoe soles; in practice, the insoles are inserted in the shoe and may be used from time to time, and by their support, thus strengthening the arch by gently and yieldingly supporting it, and with its adjustable lengthening spring B, the insole at the same time conforms to the shape of the foot resting and strengthening it, resting it and supporting the arch, affording a strengthening arch on the foot.

Having thus described my invention, what I claim as new and for which I desire Letters Patent is as follows:

1. In an arch support for shoes, an insole to be removably inserted within a shoe and having mounted on the underside thereof an elongated flat spring member, the rear end of the spring member being fastened to the underside of the heel portion of the shoe insole, the opposite end of the spring member being free, and a hood for enclosing the free end of the shank member, said hood having its rear end entirely open and being of segmental shape and extending across the insole intermediate its ends, thereby providing a wide latitude of movement of the free end of the

spring member, said free end of the spring member having a sliding engagement with the inner surface of the hood member.

2. In an arch support for shoes, an insole having mounted on the underside thereof an elongated flat spring member, the rear end of the spring member being fastened to the underside of the heel portion of the shoe insole, the opposite end of the spring member being free, and a hood for enclosing the free end of the shank member, said hood being secured to the underside of the insole with its rear entirely open and being of segmental shape so as to extend across the undersurface of the insole between its ends, thereby providing a wide latitude of movement of the free end of the spring member, with said free end of the spring member having a sliding engagement with the inner surface of the hood member.

In testimony whereof I have affixed my signature.

HARRY J. CROCKER.
